HEAT SINK FOR SEMICONDUCTOR RECTIFIERS OR SIMILAR ARTICLE

Michael A. Koltuniak, Warren, Robert G. Plantholt,
Rochester, and Claybourne Mitchell, Jr., Ann Arbor,
Mich., assignors to Controlled Power Corporation,
Farmington, Mich., a corporation of Michigan

Filed July 17, 1969, Ser. No. 18,235

Term of patent 14 years

Int. Cl. D13—03

U.S. Cl. D26—1

FIG. 1

FIG. 2

FIG. 1 is a perspective view of a heat sink embodying our novel design;

FIG. 2 is a top plan view of the same;

FIG. 3 is a bottom view of the same;

FIG. 4 is a side elevational view taken from the right side of FIG. 1; and

FIG. 5 is a front elevational view of the same.

The left side of our heat sink is the same as the right side illustrated in FIG. 4, and the rear is the same as the front illustrated in FIG. 5.

We claim:

The ornamental design for a heat sink for semiconductor rectifiers or similar article, as shown and described.
